UNITED STATES PATENT OFFICE.

WM. OSTRANDER, ISAAC D. REEDER, AND JOSEPH CORDUAN, OF BROOKLYN,
NEW YORK.

IMPROVEMENT IN THE CONSTRUCTION OF ORDNANCE.

Specification forming part of Letters Patent No. 34,977, dated April 15, 1862.

To all whom it may concern:

Be it known that we, WILLIAM OSTRANDER, ISAAC D. REEDER, and JOSEPH CORDUAN, all of Brooklyn, Kings county, New York, have invented a new and useful Improvement in the Construction of Cannon; and we do hereby declare that the following is a full, clear, and exact description of the same, reference being made to the annexed drawings, making a part of this specification, in which—

Figure I is a side elevation, partly in section, to exhibit interior construction. Fig. II is a transverse section on the line $x x$ of Fig. I, and similar letters indicate similar parts throughout the figures.

Our improvement consists in constructing a cannon by making, first, a tube of metal to constitute the bore, then winding this tube with wire, and, after affixing a suitable breech-piece, to cast brass or other suitable metal around the wire and the breech-piece, thus giving to the exterior the desired contour and binding the parts firmly together. A cannon thus constructed may have the greatest possible strength, due to the weight of metal employed, since, as is well known, the full tensile strength of metal can be in the form of wire more equally distributed throughout the gun than in the form either of a casting or a hammered mass.

The manner in which we prefer to carry out our invention is to make the tube for the bore of a skelp of steel, the abutting edges of which are to have a V-joint. This skelp (shown at a) has a flange turned up at the breech end, as at b , and a collar near the muzzle, as seen at c . A piece of iron or other suitable metal, d , is then inserted, being of proper form for a breech, and being also so shaped that a portion of it within the outline of the finished cannon will be so much smaller than the bore that the metal to be cast around shall partially inclose it to hold it in place. A close-fitting mandrel is now to be inserted into the tube as far as the breech, and the tube is then to be tightly wound with a continuous wire, e , from the flange b to the collar c , continuing the winding in successive layers until a thickness is obtained sufficient to resist the bursting pressure. This thickness will of course vary at different points in

the length of the gun, more layers being necessary near the breech than at the muzzle, as shown. The whole is now to be placed as if it were a core, in a proper mold, and a covering of gun-metal or iron, f , is to be cast around and upon it. It will be seen that the tube a extends entirely through to the face of the gun and forms part of that face, while the collar c is set back a little, so that the covering metal may at that part come close to the tube. The breech-piece d need not extend necessarily through the gun, but may be entirely inclosed, the knob of the cascabel being then formed of the covering metal.

In casting on the outer metal some difficulty will arise from the presence of air between and among the coils of wire, and causing by its expansion, when heated by the melted metal "honey-comb" spots in the casting. To obviate this we fill the spaces between the wires with some substance which will displace the air, but will not be disturbed by the heat. A preparation of the silicate of soda mixed with plumbago effects this very well, and should be applied as the wire is being wound on, so as to fill all the spaces. When the casting has cooled sufficiently, the mandrel may be drawn out and the bore polished, if necessary, or rifled, the outside finished up, and the vent drilled. If greater strength is required longitudinally than is afforded by the above construction, it may be obtained by the employment in addition of rods or bars running lengthwise over the coil of wire and closing the ends at the breech over the breech-piece; or the tube may be extended out and closed down over the breech-piece.

We claim—

Constructing a cannon by winding wire around a tube which has a breech-piece inserted, and binding the whole together by casting metal upon it, in the manner and for the purposes substantially as set forth.

WILLIAM OSTRANDER.
ISAAC D. REEDER.
JOSEPH CORDUAN.
